CLAIM

The ornamental design for a wall mount trading card display, as shown and described.

DESCRIPTION

FIG. 1 is a front view of a wall mount trading card display showing my design;

FIG. 2 is a rear view thereof;

FIG. 3 is a side view thereof;

FIG. 4 is a top view thereof; and,

FIG. 5 is a perspective view thereof with a second transparent trading card protector case shown in broken lines in a partially removed state in the display.

The broken lines illustrate structure or features which form no part of the claimed design.

1 Claim, 2 Drawing Sheets

FIG. 2

FIG. 1

FIG. 3

FIG. 4

FIG. 5
